UNITED STATES PATENT OFFICE.

LAVAN OLIVER, TILDEN B. OLIVER, AND GORGE W. WEST, OF NORTH PLEASANTON, TEXAS.

RAILWAY CONSTRUCTION.

1,207,615.

Specification of Letters Patent.

Patented Dec. 5, 1916.

Application filed May 5, 1916. Serial No. 95,665.

To all whom it may concern:

Be it known that we, LAVAN OLIVER, TILDEN B. OLIVER, and GORGE W. WEST, citizens of the United States, residing at North 5 Pleasanton, in the county of Atascosa and State of Texas, have invented new and useful Improvements in Railway Constructions, of which the following is a specification.

This invention relates to improvements in 10 railway construction.

In carrying out our invention it is our purpose to produce a metallic tie for railway rails which shall be of a simple, cheap and novel construction and which shall have 15 means associated therewith whereby the rails can be easily and quickly secured thereon.

It is a further purpose of the invention to construct a metallic rail tie having means associated therewith whereby the rails may 20 be secured thereon and further whereby the meeting ends of two rails may be connected in a solid and durable manner without the employment of angle bars, fish plates or analogous devices or without the employing 25 of the usual nuts and bolts for connecting the said rail ends.

It is also our purpose to produce a metallic tie having the general shape of an ordinary I-beam, and which has its web, upon 30 both of its sides, at points below which the rails rest, provided with bracing ribs, so constructed and arranged as to receive rail supporting members and to connect the said members between the ties, so that the rails 35 will be supported throughout the length of the track; the ties held properly spaced and sustained against movement toward or away from each other, and also whereby a considerably less number of ties will be required 40 upon the track, as the supporting members may be of any desired length.

With the above and other objects in view the improvement resides in the construction, combination and arrangement of parts set 45 forth in the following specification and falling within the scope of the appended claim.

In the drawings: Figure 1 is a perspective view illustrating rails supported upon ties and connecting members between the ties 50 as constructed in accordance with our invention, Fig. 2 is an enlarged horizontal sectional view taken through the webs of two of the ties, Fig. 3 is a detail perspective view of one end of one of the ties, Fig. 4 is 55 an enlarged detail vertical longitudinal sec-

tional view taken through the head and base flanges of one end of the said tie, Fig. 5 is a plan view of the tie with the rail securing members removed, Fig. 6 is a transverse sectional view approximately on the line with the sustaining or locking member of one of the rail securing elements, the said element being associated with the tie, Fig. 7 is a perspective view of one of the rail engaging elements looking toward the underface 60 thereof, Fig. 8 is a perspective view of one of the rail supports or chair members arranged between two of the ties, and Fig. 9 is a similar view illustrating a modified form of the rail support or chair member. 65

Each of the ties A includes a flat head 1, a flat base 2, and a centrally arranged connecting plate or web 3 for the head and base. The web 3, at the ends of the ties, is cut inwardly, the opposite walls provided 70 by the cuts being parallel, but being rounded to their connection with the head and the base.

Formed integrally with the ties and disposed preferably centrally beneath the rail 80 seats of the ties are vertically disposed brace members 4. These brace members are disposed opposite each other upon the web of the tie and are each provided with a central vertically disposed slot or channel 85 that is of a greater depth at the upper portion thereof than at the lower so that the said lower portion of the channel is formed with a lug or shoulder 5.

The head 1 of each of the ties, adjacent 90 the ends thereof, is for a determined distance thickened, as at 6, and the rail seat 7 which is arranged centrally of the said thickened portion is disposed a suitable distance below the top proper as clearly shown 95 in the drawings. The said thickened portions 6 of the head 1, to the opposite sides of the rail seat 7 are formed with transverse channels or depressions 8—8, and the opposite walls provided by these depressions are 100 inclined away from each other as clearly shown in the drawings. These channels are wider at one of their ends than at their other end so that the same will receive wedge-shaped tongues 9 provided upon the underfaces of rail engaging members 10. The members 10, upon what I will term their inner inclined and beveled edges are formed with outwardly extending ribs 11, which are adapted to contact with the longitudinal 110

edges of the base flange of the rails 12 to force the said rails centrally upon the rail seat 7, while the flanges 13 of the rail engaging members inward of the said ribs 11 5 overlying and engaging with the upper faces of the base flanges of the rail, hold the said rails down upon the rail seats and thus the members 10 effectively lock the rails to the ties. The members 10 are provided with 10 vertically disposed wedge-shaped slots 14 which register with similar slots 15 in the horizontal walls provided by the grooves 8 and these openings 15 are arranged over the web of the tie and are of a greater length 15 than the thickness of the said web. If desired the web at the portion thereof which communicates with the openings 15 may be beveled in opposite directions so as to split or divide the ductile wedge-shaped shanks 20 17 of the headed retaining members 18 and thus effectively hold the members 10 upon the ties.

It is one of the purposes of the present invention to provide means for connecting 25 or spacing the ties as well as for supporting the rails between the ties so as to reduce the number of ties employed as well as to form a firm bed or support for the rails, and therefore we provide rail supporting members 30 B each of which includes a head 17, a centrally disposed web 20 and if desired a base 21. If, however, the base is to be dispensed with the web may be widened and have its lower edge notched in a line with 35 the ends of its head. By reference to the drawings it will be noted that the web 20 projects beyond the head and base of the chair or support and also that the upper edge of the web from the ends of the head 40 is cut longitudinally in a line below the said head, whereby the web may be snugly received beneath the head of the tie and also be snugly received upon the base of the tie. The web has its ends extending beyond its

head and base a distance equaling the width 45 of the head and base of the tie to the opposite sides of the web thereof, and the ends of the web 20, at the lower corners thereof are notched, as at 22, and whereby the same will snugly engage with the shoulders 5 when the 50 ends of the webs are received within the slots of the brace members 4.

From the above description, taken in connection with the accompanying drawings, the simplicity of the device as well as the 55 advantages will, it is thought, be perfectly apparent to those skilled in the art to which such invention appertains without further detailed description.

Having thus described the invention, what 60 we claim is:

In a railway construction, metal ties including each a flat head, a flat base, a central web connecting the head and base, rails resting upon the ties, means for securing the 65 rails to the ties, vertically disposed brace members arranged in pairs upon the outer faces of each of the webs, a shoulder between each pair of brace members, members having head portions and angular webs 70 which project beyond the head, the ends of the said members being notched and adapted to be received between each pair of brace members of adjacent ties and to engage with the shoulders in the said brace members 75 whereby the heads of the said members are retained flush with the tops of the ties to underlie and support the rails between the ties.

In testimony whereof we affix our signatures in presence of two witnesses.

LAVAN ALIVER.
TILDER B. OLIVER.
GORGE W. WEST.
